COMBINED STORAGE CABINET AND RACK FOR COSMETICS OR THE LIKE

Robert Louis Ising, 6701 Boulevard E.,
West New York, N.J.

Filed Aug. 17, 1965, Ser. No. 86,613

Term of patent 14 years

(Cl. D86—10)

FIGURE 1 is a perspective view of a combined storage cabinet and rack for cosmetics or the like, showing my new design, with the cosmetic rack in a tilted position and the cabinet in an open position;

FIG. 2 is a side elevational view thereof with the rack in a vertical position having its shelf in horizontal position and the cabinet closed;

FIG. 3 is an elevational view taken from the front of FIG. 2;

FIG. 4 is a fragmentary elevational view taken from the side of FIG. 1;

FIG. 5 is an elevational view taken from the rear of FIG. 2; and

FIG. 6 is a side elevational view thereof showing the rack and its support in a collapsed position.

The broken line representation of a cosmetic bottle in FIG. 1 is for purposes of illustration only.

I claim:

The ornamental design for a combined storage cabinet and rack for cosmetics or the like, as shown and described.
